LEWIS W. CHUBB, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

PROTECTIVE APPARATUS AND SYSTEM.

1,260,643.

Specification of Letters Patent. Patented Mar. 26, 1918.

Application filed July 12, 1915. Serial No. 39,420.

To all whom it may concern:

Be it known that I, LEWIS W. CHUBB, a citizen of the United States, and a resident of Edgewood Park, in the county of Allegheny and State of Pennsylvania, have invented a new and useful Improvement in Protective Apparatus and Systems, of which the following is a specification.

My invention relates to door-operating systems for vehicles, and it has special reference to safety systems for operating doors in conjunction with the motor-control systems of electric railway vehicles and the like.

15 The object of my invention is to provide a simple and inexpensive system of the above-indicated character for preventing the opening of vehicle doors when the driving motors are in operation and for preventing the starting of the vehicle when the doors are open, whereby the liability of accidents may be reduced to a minimum.

In the prior art, various vehicle door-operating systems have been proposed, but, 25 so far as I am aware, no single system exists for coöperatively performing both of the above-mentioned functions, as each function has been effected by independent and individual apparatus, thereby requiring a 30 relatively complicated and expensive safety system.

According to my present invention, I provide a novel and simple system having the desirable characteristic of performing both 35 of the required functions reliably and effectively, as hereinafter more fully set forth.

In the accompanying drawing, Figure 1 is a diagrammatic view of a safety system embodying my invention in conjunction 40 with a motor-controlling system for electric vehicles; Fig. 2 is a view in elevation of one piece of control apparatus that is employed in the system shown in Fig. 1; and Fig. 3 is a view similar to Fig. 2 and illustrating 45 a modification thereof.

Referring to Fig. 1, the system here shown comprises a plurality of suitable doors D¹ and D² that are disposed in accordance with customary practice upon an electric railway 50 vehicle (not shown); a plurality of operating mechanisms OM¹ and OM² for the doors D¹ and D², respectively; a suitable supply circuit comprising conductors respectively marked "Trolley" and "Ground;" a vehicle-motor-control system CS, the circuits of

which are partially illustrated in connection with a master controller MC of a conventional type; a door-controlling switch DS that preferably forms a part of the master controller; a magnetically-controlled switch 60 MS that is associated with a vehicle motor in a manner to be described and which is employed in connection with the operation of the vehicle doors; and a plurality of door-restraining devices or latches RD¹ and RD² 65 that are associated with the doors D¹ and D², respectively, as hereinafter more fully set forth.

The operating mechanisms OM¹ and OM² each comprises a suitable pneumatic valve 70 member V and a pneumatically-operated piston P coöperating therewith, and that moves within a suitable cylinder 1 and is secured to the corresponding door by means of a rod 2. The piston P is held in the 75 position shown in the drawing, which corresponds to the closed position of the doors, through the agency of a suitable helical spring 3 that is disposed behind the piston within the cylinder 1. The cylinder 1 and 80 the valve V are connected by a pipe or passage 4.

The valve V may be of any suitable type and is shown as connected to a pipe or passage 5 which conducts fluid pressure from 85 any suitable source (not shown) to the body of the valve, which is normally closed except when the actuating coil 6 is energized, whereupon fluid pressure is admitted from the pipe 5 through the valve V and the 90 pipe 4 to the cylinder 1 to open the door. When the actuating coil 6 is deenergized, the cylinder 1 communicates through the pipe 4 and the valve V to an exhaust pipe or passage 7, as illustrated in the drawing, 95 whereupon the spring 3 effects the closure of the door. The valves V preferably are also severally provided with manually operable handles 6^a for emergency purposes, as set forth later.

100 The door restraining devices RD¹ and RD² each comprises a suitable actuating coil 8 for a core-member 9 that also serves the purpose of a latch by reposing in a groove or recess 10 in the top edge of the door D¹ 105 or the door D² when the door occupies its closed position. The core member 9 has its upper end provided with a movable contact member 11 that is adapted to bridge a pair of stationary contact members 12 when 110

the door is in its closed position. The actuating coils 6 and 8 are all four in series circuit relation, as set forth more fully later. The core-members 9 preferably are also provided with manually operable handles 9^a for emergency purposes, as hereinafter described.

For the purpose of supplying the motor-control system CS with a suitably low voltage, a control resistor CR of a familiar type is connected between the supply-circuit conductors Trolley and Ground, and the control system is connected between an intermediate point 13 of the control resistor 15 and a point 14 thereof that is connected directly to ground.

The door-controlling switch DS may be a separate device, if desired, but preferably forms a part of the master controller MC, 20 and is adapted to occupy a position marked "Open" that corresponds to the off position of the controller, for effecting the opening of the vehicle doors, and is adapted in all other positions of the controller to maintain 25 the closure of the doors, as indicated by the legend, "Close." Thus the operation of the doors is automatically taken out of the hands of the train operator, the doors being opened when the vehicle stops and being closed when 30 the master controller is moved to its first position, although the vehicle is not set in motion until the doors are closed.

The magnetically-controlled switch MS, best shown in Fig. 2, in its general form resembles the well-known magnetic-disk braking device that is employed in various types of watt-meters, and comprises a disk of copper or other suitable material that is secured to a shaft or axle 16 which, in turn, is 40 shown as rigidly associated with the shaft 17 of one of the propelling motors M. It will be understood that any other suitable transmission means may be employed for effecting a rotation of the disk 15 in accordance with the movement of the motor shaft 17, such as belts or gears, for example, if it is desired to place the magnetically-controlled switch MS in the body of the car rather than upon the vehicle-truck. The 50 shaft or axle 16 is suitably supported in a bearing member 18, to which are attached a pair of arms 19 that extend in opposite directions and have their ends suitably bent to receive a pair of horseshoe preferably permanent magnets, of the usual type, that have their respective polar arms disposed on opposite sides of the rotatable disk 15, whereby the disk rotates within the field of the magnets 20, in accordance with the 55 familiar watt-meter practice referred to above. The arrangement of parts is such as to allow the magnets 20 to rotatively move on the axle 16 by reason of the magnetic force between the disk 15 and the magnets 60 that is set up by the eddy currents created 65

in the disk, as will be understood. The lower end of the axle 16 is provided with a pointer or swinging arm 21. A pair of suitable springs 22 are oppositely secured to the arm 21 to bias it to a central position wherein 70 contact is effected between a contact member 23 that is secured to the arm 21 and a stationary contact member 24 that is included in the circuit of the door-actuating mechanisms, as set forth later.

75

It will be understood that during the rotation of the motor armature, the consequent rotation of the disk 15 magnetically moves the magnets 20 and the associated arms 19 in the manner above outlined, whereby the 80 contact members 23 and 24 become disengaged and the arm 21 swings outwardly to a position indicated by dotted lines 25, the direction of movement of the arm 21, of course, depending upon the direction of rotation of the disk 15.

85

Assuming that the master controller MC is moved to an operative position and that the remainder of the apparatus embodied in the system occupies the respective positions 90 shown, the operation of the system may be set forth as follows: A circuit is established from the intermediate point 13 of the control resistor CR, through conductors 26 and 27, the coöperating stationary and movable 95 contact members 12 and 11, respectively, of the door-restraining device RD² in its lower position, conductor 28, the coöperating contact members 12 and 11 of the other door-restraining device RD¹ in its lower position, 100 conductor 29, contact member 30 of the door controlling switch DS in its position marked "Close," conductor 31, control fingers 32 and 33 which are bridged by contact segment 34 of the master controller, the actuating coil 105 35 of one of the motor-controlling switches, control fingers 36 and 37 which are bridged by contact segment 38, conductor 39 and through the point 14 of the control resistor CR to ground. The controlling motors may 110 thus be accelerated in accordance with any suitable practice, and inasmuch as the particular control system employed is not material to my present invention, I have not deemed it necessary to show or describe any 115 further operation of such a control system.

Assuming that the vehicle is being brought to rest, the master controller having been returned to its off position, the door-control switch DS has thus been moved to its position marked "Open," whereupon, after the vehicle has stopped, a circuit is established from the conductor 26 through conductor 40, contact member 41 of the door-controlling switch DS in its position marked "Open," 120 conductor 42, coöperating stationary and movable contact members 24 and 23, respectively, of the magnetically-controlled switch MS, the arm 21 of the switch, conductor 43, the actuating coil 8 of the door- 125 130

restraining device RD^2 , conductor 44, the actuating coil 6 of the valve V that corresponds to the door D^2 , conductor 45, the actuating coil 8 of the door-restraining device 5 RD^1 , conductor 46, the actuating coil 6 of the other valve V and conductor 47 to the negative conductor Ground.

The valves V are thus opened to admit fluid pressure to the cylinders 1 and the restraining devices RD^1 and RD^2 are lifted, whereby the doors D^1 and D^2 may be fully opened. At the same time, the coöperating contact members 11 and 12 of each of the restraining devices RD^1 and RD^2 become 10 disengaged and, consequently, the circuit of the motor-control system CS is broken at both of the contact members 11 and also at the contact member 30 of the door-control switch DS. As a result, the motor-control 15 system cannot be energized, even though the door-controlling switch DS is returned to its positions marked "Close", until the doors D^1 and D^2 have been closed, when the core members 9 of the restraining devices RD^1 20 and RD^2 will drop into the recesses 10 of the doors.

To close the doors D^1 and D^2 and again render the motor-control system operative, it is only necessary to actuate the master 25 controller to its initial operative position, whereby the door-controlling switch DS is moved to its positions marked "Close". In this way, the actuating circuit of the door-operating mechanisms is interrupted and 30 the springs 3, acting upon the pistons P, close the doors. The various parts then occupy the positions shown in the drawing and already described, whereby the motor control 35 system CS may be again operated to accelerate the vehicle.

It will be noted that I have thus provided a safety system for electric railway vehicles wherein a single device, namely, the purely magnetically-controlled switch MS 40 directly controls the circuits of the door-actuating mechanisms and indirectly controls the governing circuits of the motor-control system CS, the switch MS thus directly preventing the opening of the vehicle 45 doors until the propelling motors have come to a standstill and the restraining devices RD^1 being dependent upon the position of the switch MS for performing their functions in connection with the motor-control 50 system.

In Fig. 3, a modification of the magnetically-controlled switch, shown in Fig. 2, is 55 illustrated and comprises a suitable single horse-shoe preferably permanent magnet 48 that has its north and south pole arms, marked "N" and "S", respectively, bent over in the manner shown to partially inclose a rotatable disk member 49, preferably of tungsten steel or some other material 60 having relatively high magnetic retentivity

and coercive force. The magnet 48 is associated with the bearing-member 18 in the same manner as the magnets 20 are secured to the bearing-member 18 in Fig. 2, and the disk 49 is secured to the axle 16, which is 70 again driven in accordance with the movements of the propelling motor in any suitable manner.

In the device just described, consequent poles N' and S' are induced in the disk 49 75 at points respectively opposite the north and south poles of the permanent magnet 48, and upon rotation of the disk 49, the magnetic attraction exerted between the disk and the magnet serves to effect a predetermined rotative movement of the magnet to 80 vary the position of the contact-carrying arm 21.

By suitable design of parts, the relative forces exerted by the actions of hysteresis 85 and of eddy currents, respectively, may be proportioned to permit of the desired operation of the switch.

It has been found by experiment that the position taken by the arm 21 upon rotation 90 of either of the disk members 15 and 49, depending upon which particular construction is employed, is independent of the speed of the disk within predetermined limits and that, consequently, the operation 95 of the magnetically-controlled switch MS is effective and reliable throughout the range of the speed of the operating motor.

It should be observed that if the brakes should be released when the vehicle was 100 standing on a grade, the vehicle could start with the doors open, the motor controller, of course, occupying its off position at this time. However, the magnetic action of the switch MS would immediately effect the disengagement of the coöperating contact members 24 and 23, and the actuating circuit of the door-operating mechanisms would be deenergized, whereby the vehicle doors would immediately close. Although the co- 110 operating contact members 11 and 12 would then effect engagement, the propelling motors, of course, would not become operative unless the master controller was subsequently moved to an operative position. 115

I have made provision for operation of my safety system under certain emergency conditions, as follows. If the supply-circuit energy should be interrupted, the doors could be manually operated by the handles 120 6^a of the valves V and the handles 9^a of the door-restraining devices RD^1 and RD^2 , as will be understood. Any other suitable means for manually operating the doors may be employed, if desired.

However, such manual operation may be dispensed with by providing an emergency source of energy, such as a battery B, which is adapted to be connected through a suitable switch SW and the auxiliary contact 125 130

members 51 of a "line relay" LR, of a familiar type, in its lower position, to the points 13 and 14 of the control resistor CR. The actuating coil of the relay is connected 5 to the supply-circuit conductors Trolley and Ground, and the relay is held open so long as the supply-circuit voltage is uninterrupted. Upon a failure of the voltage, the relay drops to connect the battery in circuit, 10 whereby the doors may be operated in the usual manner.

I do not wish to be restricted to the specific circuit connections or construction and arrangement of parts herein set forth, inasmuch as various modifications thereof may be made without departing from the spirit and scope of my invention. I desire, therefore, that only such limitations shall be imposed as are indicated in the appended 20 claims.

I claim as my invention:

1. In a door-operating system for vehicles, the combination with a movable door and actuating means therefor, of a motor-control 25 system associated with said actuating means, means dependent upon predetermined conditions for preventing movement of said door, and means dependent upon said first means for preventing operation of said control system when said door occupies a certain position.

2. In a door-operating system for vehicles, the combination with a movable door and actuating means therefor, of a motor-control 35 system associated with said actuating means, means dependent upon movement of the vehicle for preventing opening of said door, and means dependent upon said first means for preventing operation of said control system when said door is open.

3. In a door-operating system for vehicles, the combination with a movable door and electrically-controlled actuating means therefor, of a motor-control system electrically 45 associated with said actuating means, means dependent upon movement of the vehicle for maintaining the circuit of said actuating means inoperative, and means actuated in accordance with the condition of said circuit and also dependent upon the position of said door for rendering said control system operative or inoperative.

4. In a door-operating system for vehicles,

the combination with a movable door and electrically-controlled actuating means therefor, of a motor-control system electrically associated with said actuating means, means magnetically dependent upon movement of the vehicle for maintaining the circuit of said actuating means inoperative, and switching means having an actuating coil connected in circuit with said actuating means for preventing the operation of said control system when said door is open.

5. In a door-operating system for vehicles, 65 the combination with a movable door and electrically-controlled actuating means therefor, of a member adapted to move rotatively while the vehicle is in motion, magnetizing means actuated through magnetic action 70 upon said member, and switching means associated with said magnetizing means for energizing said door-actuating means only when said member is stationary.

6. In a door-operating system for vehicles, 75 the combination with a movable door and electrically-controlled actuating means therefor, of a motor-control system electrically associated with said actuating means, a member adapted to move rotatively while the 80 vehicle is in motion, and switching means controlled by magnetic action upon said member for energizing said door-actuating means only when said member is stationary.

7. In a door-operating system for vehicles, 85 the combination with a movable door and electrically-controlled actuating means therefor, of means dependent upon the movement of the vehicle for maintaining said actuating means inoperative, and means for preventing the operation of the vehicle when said door is open.

8. In a door-operating system for vehicles, the combination with a movable door, electrically-controlled actuating means for said 95 door, and a motor-control system combined with said actuating means, of electrically-controlled means for preventing the operation of said door while the vehicle is in motion, and means for preventing the operation of the motor-control system when said door is open.

In testimony whereof, I have hereunto subscribed my name this 26th day of June, 1915.

LEWIS W. CHUBB.
